UNITED STATES PATENT OFFICE.

JOHN H. DEQUER, OF KANSAS CITY, MISSOURI.

THERMOMAGNETIC THERAPEUTIC APPLIANCE.

1,391,762.

Specification of Letters Patent. Patented Sept. 27, 1921.

Application filed May 1, 1920. Serial No. 378,217.

To all whom it may concern:

Be it known that I, JOHN H. DEQUER, a citizen of the United States, residing at Kansas City, county of Jackson, and State 5 of Missouri, have invented certain new and useful Improvements in Thermomagnetic Therapeutic Appliances; and I do hereby declare the following to be a full, clear, and exact description of the invention, such as 10 will enable others skilled in the art to which it appertains to make and use the same.

This invention relates to improvements in that type of thermo-magnetic therapeutic appliances which employ a non-conducting 15 base supporting a coiled electrical conductor to provide both a magnetic field and a heating zone when connected in circuit with a suitable electrical current.

The valuable therapeutic results obtained 20 with such appliances, in the treatment of numerous ailments of the human organism, are now well understood, whether the appliance be in the nature of a blanket, robe, suiting, bandage, pad, hood, mask, gaunt- 25 lets, stockings or otherwise.

With my invention, maximum induction and a moderated heat are desired, and it may be said at the outset, therefore, that the coiled conductor should be of comparatively 30 low resistance, as otherwise, if a high resistance conductor was employed, owing to the length of the conductor required, the heat generated would be so intense as to ignite any fabric that might be satisfac- 35 torily used in the make up of the appliance, while at the same time it would substantially cut down the magnetic induction.

While the present invention broadly involves a novel system of wiring such a 40 blanket, robe or other flexible covering with a plurality of serially co-acting circuit coils as well as the installation of a selective switch arrangement therefor, whereby the distribution, regulation and control of a 45 variably applied degree of heat may be efficiently carried out, still there are other important features of improvement involved, with reference to co-acting appliances accessory thereto and details of equipment 50 generally, including a reinforcing protective tube for the various terminal connections, all of which features are believed to be new in the art and of distinctive advantage in overcoming serious objections 55 heretofore encountered.

The several objects and advantages of the instant invention will be so clearly apparent, as incidental to the following disclosure, that it would only be undesirable surplusage to refer further to the same initially, and with these prefacing remarks, and for a better understanding of the ensuing claims, reference will be had immediately to the accompanying drawings, forming a part of this application, in which 60 drawings—

Figure 1 is a plan view of a blanket equipped with my improvements, broken away centrally and with its top or inner covering omitted to show clearly the serially 70 co-acting coil circuit system of wiring, and a suitable switchboard arrangement being illustrated diagrammatically at the upper right hand corner; Fig. 2 is a fragmentary cross-sectional view, on an exaggerated 75 scale, taken along the line 2—2 of Fig. 1; Fig. 3 is a top plan view of a local induction pad, which is a special co-acting accessory of the blanket proper; Fig. 4 is a cross-sectional view thereof taken along the 80 line 4—4 of Fig. 3; and Fig. 5 is a longitudinal sectional view through one of the reinforcing protective cones, one of which is associated with the terminal connections for the blanket, although not shown at Fig. 85 1, as well as with the local induction pad, as illustrated, and in fact with any other appliance used as an accessory to the blanket proper or its equivalent.

The numeral 5 designates a thin sheet of 90 rubberoid or other freely flexible insulating or non-conducting material, on which is laid and suitably secured the several tortuous windings of the serially co-acting circuit conductors, disposed in juxtaposition as 95 shown, and these intermediate elements are associated with a basic or outer layer 6 of thick wool and a top or inner covering of outing flannel, which latter may be secured to the layer 6 by means of snap buttons, or other readily detachable securing means, not necessary to illustrate. Is also obvious that these encompassing layers may be of any other suitable material and of several thicknesses if found expedient.

At Fig. 1 there is shown a series of three circuit conductors, which are respectively indicated at 1, 2 and 3, and each of which traverses substantially the whole heating area of the blanket in contiguous paths, but 100 105 110

owing to their being connected up in series, as will hereinafter appear, by the proper manipulation of a suitable selective switch, they may be caused to function as heating coils of one, two and threefold lengths, thus establishing temperatures of varying degrees while at the same time influencing the lines of magnetic force, and hence regulating the intensity of the field of magnetic induction.

For convenience in tracing out this improved special arrangement, the individual coil complements are illustrated by heavier and lighter lines, but as a matter of fact all of these conductors are of the same diameter, and are preferably in the nature of light cables, each formed of twelve strands of #80 diamond drawn fine copper wire covered with double silk insulation or other suitable insulation material.

The number of ampere turns of each coil conductor should be approximately such that, where all three of the coil complements are cut into action as when in circuit with a current of 110 volts with a flow of approximately 5 amperes, the resistance would generate a heat not to exceed say about 120° Fahrenheit. With the switch thrown to cut in only two of the coil complements, the temperature would be lowered to about 110°, while with only one coil complement functioning the degree of heat would be further reduced to about 100°.

From the foregoing it will be apparent that in reality I provide for substantially one and the same continuous heating area in all instances, encompassing approximately the entire upper or inner surface of the blanket, but which heating area is under a graduate control to emit heat of three different degrees of desired intensity, and these graduate subdivisions may be appropriately termed the maximum, intermediate and minimum circuit zones.

In order to attain this desired functioning, the entrant end of each of the three coil complements 1, 2 and 3 is respectively connected to contact points 11, 12 and 13 of a suitable selective switch, conventionally illustrated as a three-way switch having the swinging blade 4, the pivotal end of which latter is in electrical connection with a short conductor 8 leading from the entrant terminal 9 for the exciting current source. The exit end of the line 1, or anterior coil complement leads out initially to the return terminal 10 of the source of current supply, but the exit end of the successive coil complement 2 does not lead out initially to the terminal 10, being joined to the entrant end of the line 1, as indicated at 14. Analogously, the exit end of the line 3 is joined to the entrant end of the line 2, as at 15.

Each of the coil complements is provided with a signal lamp, indicated respectively

at 21, 22 and 23, mounted on the switchboard in circuit with their complementary contacts 11, 12 and 13, the switchboard itself being designated in dotted outline by the numeral 16, and obviously may be formed of any suitable material, such as two thicknesses of fiber board of proper dimensions, which may be secured in position by screws or otherwise.

The switchboard connecting conductors to and from the coil complements are preferably of heavier construction than the actual coil lines (to afford a substantial protection against undue breakage at the switchboard position) and may each comprise a three-ply braided cable, individually formed analogously to the lighter cables, merging into the lighter cables 1, 2 and 3 at different positions along the lines, both toward the entrant and exit ends thereof, as would be indicated by the groups 17 and 18 of three-ply construction. In addition to reinforcing the joinder between the switchboard conductor leads and the coil complements' ends, this stepped feed arrangement at 17 and 18, it is believed, has another important feature of relieving the fine wire coil complements from having too sudden a load or electrical stress placed thereon, as the switch as initially closed to cut in the outside current supply.

At one corner of the switchboard there is also mounted an auxiliary switch arrangement, adapted for controlling the passage of the current through one or more attached accessory therapeutic appliances, and for this purpose I have conventionally illustrated a pair of two-point switches, each having a swinging contact arm indicated respectively at 19 and 20.

The switch arm 19 is pivotally mounted at 24, in circuit with a short connection 25 from the exit end of the coil 1, and cooperates with the contact 26, of a branch line 27, as well as with a contact terminal 28 of a T-conductor 29 in the main outlet line, the opposite end of which T-conductor provides a pivotal support 30 for the switch arm 20.

The switch arm 20 in turn cooperates with a contact 31, of a second branch line 32, and likewise with a contact terminal 33 of a second T-conductor 34, the opposite end of which latter provides the return terminal 10 to the source of current supply.

Each of the branch lines 27 and 32 has a signal lamp in its circuit, as indicated at 35 and 36, and also each of these branch lines has a terminal plug socket, designated at 37 and 38, coacting with complementary plug sockets in circuit with the T-conductors 29 and 34. For convenience of reference, the branch lines 27 and 32 may be appropriately termed the U-branches in distinguishing from the short connections in the main outlet line referred to as T-conductors.

At Figs. 3 and 4 there is illustrated a novel form of a locally manipulative induction pad, which is peculiarly appurtenant as a co-acting accessory of the blanket *per se*, or its equivalent, in the topical treatment of the thoracic, abdominal and pelvic regions especially, for a more speedily effective relief from congested and painful conditions thereof.

10 This local induction pad consists of an upper and a lower section 40 and 41, respectively, composed of a closely woven cloth fabric, or other suitable material, which may be of circular contour, and the upper section 15 being of a larger area than the lower one, so that it may be warped or dished upwardly and provide a substantial interior space between the sections, when the peripheral edges thereof are secured in congruent position. 20 This latter may be accomplished by the interposition of a spacing ring 42, which may be of a suitable light metal if desired or of other material, to which the edges of the fabric sections 40 and 41 may be detachably secured, as by snap buttons 43 or otherwise.

Each of the pad sections are centrally apertured, as at 44 and 45, to receive the ends of a tubular core spool or barrel 46, 30 of an induction coil element, having the upper and lower disk flanges 47 and 48 for detachably supporting the inner edges of the fabric sections, which may be held by snap buttons 49 or otherwise.

35 To the inside face of the upper fabric section there is stitched, or otherwise secured, an insulated cable 50, of substantially the same form as the blanket coil cables, it being spirally wound in close convolutions from 40 its outer end 51, toward the peripheral edge of the section, to its inner end 52 toward the center thereof. An analogous cable 53 is laid upon the inner face of the lower fabric section, its inner end being indicated at 54 45 and its outer end at 55.

56 designates a soft iron coil wound around the barrel 46 and provides the core proper of the induction coil element. This coil 56 is enveloped by a cylinder 57 of insulating material, and around the latter is wound a plurality of layers of an insulated cable 60, of substantially the same style as the fine wire cables of the pad sections and blanket, and the coil 60 is encompassed by a 55 second cylinder 61 of insulation material.

One end 58, of the coil 60, is connected with the inner end 52 of the upper fabric section coil, while the other end 59 thereof is analogously connected to the inner end 54 60 of the lower fabric section coil, so that the coils of these upper and lower fabric sections are connected in continuing series through the coil 60 of the housed induction coil element.

65 Radial resilient strips 62 and 63 are re-

spectively associated with the inner faces of the upper and lower fabric sections to provide arched and straight flexing stay supports therefor, which allow for a vibratory and suctional massaging motion, in the application of the induction pad, and also permitting of the centralizing of the magnetic charge at any desired position on the body, to relieve pain and local congestions, as well as adapting the lower pad section to accommodate itself to the contour of the body. A suitable coiled spring construction might be made to serve the same purpose as these springy stays.

The free ends 51 and 55, of the cables 50 and 53, are connected to a pair of braided current applying cables, indicated at 64 and 65, which in turn are in circuit with the contact elements 66 and 67 of the usual type of hard rubber plug support 68, but in the ordinary connections between these braided cables and the hard rubber plug support, there is a strong tendency in actual use of the wires being wiggled therein, and thus becoming abraded and breaking with a consequent arcing of the current at that position as is well understood.

To avoid just such objections, I have devised a special means for the protective reinforcement or staying support of the connection of the braided cables at the plug, which consists of an open-ended conical tube 69, that may be formed of a stiff cloth fabric, such as heavy braided cotton, or other suitable material, the base of which conical 100 stocking-like element is fitted over the plug support and secured thereto by a crimping rim 70, while the apex thereof is clamped rigidly to the cables, at a position substantially distant from the plug element, as by 105 a clamping band 71, the spaced ends of which may be drawn together by a screw 72 or equivalent means.

One of these devices is shown in sectional detail at Fig. 5 and in applied use with the 110 induction pad at Fig. 3, but while the device is not shown at Fig. 1, owing to lack of proper illustrative space, it is to be understood that one of these protective cones is also associated with the blanket construction, and in fact it is attached to the lamp cord connections, or current applying cables, of each and everyone of the therapeutic accessory appliances utilizable with the blanket or its equivalent.

115 It is not believed to be desirable to encumber this application with specific illustrations and descriptions in detail of all of the accessory therapeutic appliances that may be coactively associated with the improved blanket, as I claim no particular novelty in them *per se*, with the exception of the local induction pad illustrated, but it may be well to briefly refer generally to the 125 class of limb induction socks or stockings, 130

which are commonly employed in association with the blanket where it is desired to intensify the induction at the lower extremities, as for instance in the cases of 5 swollen, painful or rheumatic conditions of the feet, ankles and legs. These socks or stockings (and even gauntlets where the treatment is for the hands and arms) are formed substantially in the same manner and 10 of the same materials as the blanket structure, excepting that they need only have one coiled circuit line (that is to say one for each member connected in series) as the current therethrough, and hence the thermic 15 and induction requirements for any patient, may be fully regulated by the graduate control of the circuits around the blanket structure, and this whether the stockings are used alone with the blanket or in conjunction 20 with the local induction pad, heretofore described or other accessory therapeutic appliance, all of which will be clearly apparent.

Operation.

25 Assuming first that the blanket is being used alone, as when the auxiliary switch arms 19 and 20 are thrown to the full line positions, to cut out the U-branches 27 and 32 which are respectively adapted to include 30 an accessory appliance in circuit with the blanket's coil element or elements, then with the selective switch arm 4 thrown to the contact 11, the other two contacts 12 and 13 being thereby positively maintained open, the 35 path of the incoming current (say from an electric light fixture) will be as follows:—

Entrant terminal 9, short connection 8, contact 11, signal lamp 21, coil complement line 1, from whence it leads directly out 40 initially by way of 25, 19, 29, 20, 34 to the exit terminal 10, and back to the source of supply, covering only the minimum or first zone circuit belt as it will not have traversed either of the coil complements 2 or 3. With 45 the switch arm 4 thrown to the contact 12 (contacts 11 and 13 being cut out) obviously the circuit from the switch arm will continue by way of contact 12, signal lamp 22 and initially around the coil complement 2, from 50 whence it enters the coil complement 1, at the joinder 14, and finally leads out from the line 1 at 25 as heretofore described, having traversed both of the coil complements 2 and 1 and hence the intermediate or second 55 zone circuit belt. Analogously, with the switch arm 4 thrown to the contact 13, contacts 11 and 12 being cut out, the flow will be then by way of contact 13, signal lamp 23, initially around coil complement 3, entering 60 the line 2 at 15, thence around coil complement 2, entering the line 1 at 14, and finally leading out from the line 1 at 25, as before described, having traversed all three of the coil complements and hence the maximum or 65 third zone circuit belt. Obviously, in all

three of the instances cited, the proper signal lamp will be lighted to indicate which of the circuit zone belts is being traversed.

Assuming now that it is desired to use the induction pad, and that the U-branch 27 is 70 the branch customarily employed for that purpose (although either U-branch may be used for any accessory attachment) then the switch 20 remains positioned as in Fig. 1, but the auxiliary switch arm 19 is shifted to 75 engage the contact 26, leaving a gap between 24 and 28. With the contact pins 66—67 now plugged into the sockets 37, the circuit from 25 will be completed through the local induction pad by way of 24, 19, 26, 27, includ. 80 ing the signal lamp 35, thence continuing by way of 29, 30, 20, 33, 34 and to the exit terminal 10. If, on the other hand, the accessory appliance is coupled up in the branch 32, instead of in the branch 27, then the 85 switch arm 19 would be positioned as in full lines at Fig. 1, closing the gap between 24, and 28, while the auxiliary switch arm 20 should be shifted from the contact 33 to the contact 31, leaving a gap between the switch 90 arm pivot 30 and the contact 33, whereupon the circuit from 25 would be completed through the accessory appliance, be it the induction pad, socks or other equipment, when its contact pins are plugged into the adjacent sockets 38, by way of 24, 19, 28, 29, 30, 95 20, 31, 32, including the signal lamp 36, and out through 34 into 10, omitting the branch 27 entirely. If it be desired to use both the 100 induction pad and the socks, or other accessory appliance, at the same time, the switch 19 is thrown to the contact 26 while the switch 20 is thrown to the contact 31, when gaps will be provided between 24—28 as well as between 30—33, whereupon the 105 circuit will include both U-branches 27 and 32, including their signal lamps and plugged in accessory equipment, the circuit from 25 being then by way of 24, 19, 26, 27, 37, 29, 30, 20, 31, 32, 38, 34 to 10.

110 Thus it will be seen that this auxiliary switching arrangement of itself serves a far reaching advancement in the art, in addition to and in co-acting combination with the improved blanket structure, enabling the employment of various important accessory appliances in conjunction therewith, and all being under especially effective thermal and magnetic regulation by virtue of the improved graduate control of the coil complements of the blanket.

115 Also, it may be said that, although in actual practice I find that three blanket coil complements augmented by only a pair of accessory equipment branch lines will apparently suffice all emergent purposes, these numbers may be varied by proper modifications, if found later to be expedient, provided the essential features of the invention are still incorporated.

Therefore, while I have thus made a complete disclosure of the improvements, it may later be found to be desirable or expedient to make alterations in the structural formation and arrangement of the elements thereof, but without departing from the spirit of the invention, and it will be accordingly understood that I do not limit myself necessarily to the exact details as shown and described, excepting as they may come within the purview of the ensuing claims, when fairly interpreted in the light of the specification and understood equivalents.

What I do claim, as new and patentable, is:—

- 5 1. A thermo-magnetic therapeutic appliance, embodying a base support of suitable material; resistance conducting means comprising an anterior and a successive coil complement wound on said base support, each having a separate entrant contact end with the exit end of said successive coil complement connected in series with the entrant end of said anterior coil complement to provide for continuous circuits of varying lengths having a single final exit within the zone of said base support; and switching means associated with said respective entrant contact ends for selectively closing a shorter 20 circuit through said anterior coil complement and a longer circuit through said successive and anterior coil complements.
- 25 2. A thermo-magnetic therapeutic appliance, embodying a base support of suitable material; resistance conducting means comprising anterior and successive coil complements wound on said base support, each having a separate entrant contact end with the exit end of each successive coil complement connected in series with the entrant end of its immediately preceding coil complement to provide for continuous circuits of varying lengths having a single final exit within the zone of said base support; and switching 30 means associated with said respective entrant contact ends for selectively closing a shorter circuit through said anterior coil complement and longer circuits through successive and anterior coil complements.
- 35 3. A thermo-magnetic therapeutic appliance, embodying a base support of suitable material; an electrical resistance conductor suitably coiled thereon and providing an entrant contact end and an exit end, for connection in circuit with an electrical current source; a switch control for said entrant contact end; a switch controlled branch connected in series with said resistance conductor coil, providing contact making elements for the attachment of an accessory therapeutic appliance; and an auxiliary switch associated with said branch for cutting the current therethrough, as desired, substantially as described.
- 40 4. A thermo-magnetic therapeutic appliance, embodying a base support of suitable material; a plurality of electrical resistance conductors, each comprising a coil complement, wound thereon and so connected in series as to provide independent entrant contact ends and a common exit end, for connection in circuit with an electrical current source; a switch controlled branch connected in series with said coil complements, providing contact making elements for the attachment of an accessory therapeutic appliance; and an auxiliary switch associated with said branch for cutting the current therethrough, as desired, substantially as described.
- 45 5. A thermo-magnetic therapeutic appliance, embodying a base support of suitable material; a plurality of electrical resistance conductors, each comprising a coil complement, wound thereon and so connected in series as to provide independent entrant contact ends and a common exit end, for connection in circuit with an electrical current source; a plurality of switch controlled branches connected in series with said coil complements, providing contact making elements for the attachment of accessory therapeutic appliances; and auxiliary switching means associated with all of said entrant contact ends, for selectively closing a circuit through any one thereof; and auxiliary switching means associated with said branches, for cutting the current through any one or more thereof, as desired, substantially as described.
- 50 6. A thermo-magnetic therapeutic appliance, embodying a base support of suitable material; a plurality of electrical resistance conductors, each comprising a coil complement, wound thereon and so connected in continuing series as to provide independent entrant contact ends and a common exit end, for connection in circuit with an electrical current source; a plurality of switch controlled branches connected in series with said coil complements, providing contact making elements for the attachment of accessory therapeutic appliances; separate signal electric lamps included in circuit with each of said coil complements and each of said branches; and auxiliary switching means associated with all of said entrant contact ends, for selectively closing a circuit through any one thereof; and auxiliary switching means associated with said branches, for cutting the current through any one or more thereof, as desired, substantially as described.
- 55 7. As an accessory equipment for thermo-magnetic therapeutic appliances, a locally utilizable induction pad embodying an upper and a lower flexible section support resiliently spaced apart to provide a hollow interior, each section having an electrical

resistance conductor suitably wound thereon as coil complements and terminating in a pair of lead out ends for attachment with lamp cord connections; and a magnetic induction element, housed by said hollow interior, including an insulated coil of fine wire cable, wound around a suitable soft iron core, and connected at its ends in series with and intermediate of the coil complements of said flexible sections, substantially as described.

8. As an accessory equipment for thermomagnetic therapeutic appliances employing lamp cord leads with socket plug connec-

tions, a reinforcing protective device for 15 encompassing the connections of the lamp cords with their socket plugs, embodying a hollow elongated conical element formed of suitable stiff material; means for securely attaching the hollow base of said conical 20 element around a socket plug; and means for clamping the apex portion thereof around the lamp cord connections at a position substantially distant from the socket plug, substantially as described.

25 In testimony whereof I affix my signature.

JOHN H. DEQUER.
